Application January 12, 1940, Serial No. 313,568

6 Claims. (Cl. 196—32)

This invention relates to a modification in the process of transferring of components from their solutions in one phase to another phase which is substantially immiscible in the first phase, and more particularly deals with an arrangement of the flows of the two phases so as to improve the efficiency of extraction.

It is the purpose of this invention to conduct the flow of the liquid containing extractable material and the extracting solution so as to attain maximum efficiency.

In our improved method of extraction, the solution phase containing material to be extracted is divided in a manner to produce at least two solution fractions, one of which contains portions of components of said material relatively easy to remove and one or more of which contains components more difficult to remove.

As a result of the distribution in the various fractions of the components of the material to be transferred, the ease of transferring the material to the other phase is different for each fraction. The "ease of transference" as herein defined depends upon the initial and final concentrations of the component or components in the fraction as well as upon their respective extraction coefficients.

The extraction coefficient of a given component is defined as the concentration of the solute in the extracting solvent divided by the concentration of the same solute in the solution phase at equilibrium; and the ease of transference may be measured by the inverse volume ratio of extracting solvent to solution which is required to reduce under a standard set of conditions the concentration of transferable material in the solution to a predetermined final concentration. In other words for increasing coefficient of extraction, starting with a given concentration of solute, less extracting liquid is required to reduce its concentration to a certain level and hence the ease of transference rises with increasing coefficient of extraction. Conversely, with increase in concentration, for a given coefficient of extraction, more solvent is required to reach this level and hence the ease of transference decreases with increase in starting concentration.

In carrying out the process, the several fractions are subjected to extraction preferably in countercurrent, in the following manner:

A first fraction containing the components of lowest ease of transference is treated separately with a certain volume of extracting solvent. The same volume of the same solvent was used previously to extract a mixture of the resulting

treated first fraction with other treated or untreated fractions of greater ease of transference. By this procedure the first fraction is treated with a higher ratio of solvent to solution than the mixture. For example, assuming that extraction be carried out in an extraction tower in which the solvent is introduced near one end; assuming further that the solution to be extracted be divided into two fractions as described before, then the fraction containing the components of lowest ease of transference is introduced at the opposite end of the tower, and the other fraction is introduced at a point intermediate between the points of entrance of the first fraction and the solvent. Both fractions flow in countercurrent to the solvent and are combined in the tower. The combined extracted fractions are then withdrawn at the end of the tower near the point of entrance of the solvent.

It will be seen that by this method of flow the fraction containing the components having the lowest ease of transference is extracted with a higher solvent ratio than the other fraction which is treated in combination with the first extracted fraction only. If more than two fractions are produced, the other fractions may be introduced at points between the two end fractions in the order of their relative ease of transference.

The effect of this method is that for a given over-all ratio of selective solvent to solution containing extractable components, the fraction containing the most difficultly removable components receives treatment with a much larger quantity of extracting solution per unit volume than the fractions containing the components easier to remove. As a result, the content of removable components in the solution phase can be lowered to a level far below that which could be achieved by conventional treatment under otherwise similar conditions with the same over-all ratio of selective solvent to solution containing the same extractable components.

This method shows improvement over the conventional countercurrent extraction primarily, when upon fractionation a marked change in the ease of transference of the components in each of the fractions is effected, and more particularly when components of widely different coefficients of extraction are accumulated in different fractions, preferably the fraction containing the components of lowest coefficient of extraction being as small as possible.

According to the process, this small fraction is treated with a relatively high ratio of solvent

and the more difficultly extractable components are more completely removed.

Likewise if the solution contains components of approximately equal extraction coefficients it is advantageous to accumulate at least some of them in one fraction and simultaneously to produce a second fraction containing a lower concentration of these components. The components in the first fraction on account of the higher concentration have the lower ease of transference and this fraction should be treated with a greater solvent to solution ratio than the second fraction.

The main advantage of the extraction as carried out according to this invention is an increase in over-all extraction efficiency making it possible to obtain a given result with a much lower ratio of solvent to total solution than has heretofore been possible.

Further to explain this invention, a specific application will be described in detail; namely the extraction of mercaptans from hydrocarbon oils with aqueous solutions of caustic alkali.

It is known that mercaptans and other weak organic acids such as alkyl phenols, thiophenols, etc., can partially be removed from their solutions in sour hydrocarbon oils by extracting them with aqueous solutions of caustic alkali, to produce a spent aqueous solution containing absorbed organic acids and a treated hydrocarbon oil, and separating the two liquids from one another. The spent aqueous solution may then be regenerated as by steam stripping to make it fit for further extractions.

When sweetening sour hydrocarbon distillates by extraction of mercaptans, it is necessary to reduce the mercaptan sulfur content of the distillate to about .0004% as determined by the method of Tamme and Ryland (Ind. Eng. Chem. Anal. Ed. vol. VIII, 1936, p. 16). To achieve this result with a given extracting medium and given apparatus, it is necessary to maintain a certain minimum ratio of extracting solution to hydrocarbon oil which minimum can be calculated, if the types and amounts of the various mercaptans in the sour distillate are known. In general, high boiling mercaptans are more difficult to remove by extraction than lower boiling ones, because the former are less soluble in the extracting solvent (i. e. the aqueous caustic alkali solution) than the latter. Therefore where the removal of high boiling mercaptans is involved, a high ratio of selective solvent to organic liquid is usually required. This in turn necessitates high steam consumption for regeneration of the spent solvent and is responsible for high solvent circulation costs.

Our method comprises the steps of first separating the organic liquid containing the mercaptans by fractional distillation into at least two fractions, one containing low boiling portions of the mercaptans, the other containing higher boiling portions. The distillation method is used because the differences in boiling points provide a convenient basis for the segregation according to the extraction coefficients of the mercaptans in the resulting fractions. As is known the extraction coefficients for the normal mercaptans between hydrocarbon distillates and aqueous alkaline solutions decrease with increase in their boiling points, and hence fractional distillation offers a simple means for preparing fractions of varying ease of transference.

The fractions are then treated in a counter-current system with an aqueous alkali solution

to remove the mercaptans. The aqueous alkali solution and the fraction containing the higher boiling mercaptans, i. e. those having the lowest ease of transference are fed at opposite ends of the system. The fraction containing the lowest boiling mercaptans is introduced at a point intermediate between the entrance points of the highest boiling fraction and the aqueous solution. Other intermediate boiling fractions are introduced at points between the two end fractions, the order of introduction of these several fractions being according to the order of their relative ease of transference. This may not be necessarily the order of boiling ranges since the effect of the initial concentration of mercaptans and of mercaptan configuration may at times alter this order. As is known, in general, the extraction coefficients of different mercaptans with the same number of carbon atoms, decrease with increased degree of branching. If desired, the exact order of ease of transference of the several fractions may be determined experimentally by extraction tests under a standardized set of conditions. As the several fractions flow counter-current to the aqueous solution, they are combined and the combined fractions, substantially free of mercaptans are removed from the system at a point near the point of introduction of the aqueous alkaline treating solution.

Our invention is further illustrated in the accompanying drawing representing a flow diagram of a preferred form of our process, in which a sour hydrocarbon distillate, such as a gasoline distillate, is sweetened by extraction of mercaptans with an aqueous caustic alkali, preferably containing a solutizer for the mercaptans, such as potassium isobutyrate. The sour distillate enters heater 1 through line 2 from a source not shown, and is fractionally distilled in fractionating column 3 to produce three fractions. It is, of course, understood that any desired number of fractions may be produced such as 2, 4, 5, etc., depending entirely on convenience and/or economical considerations. These three fractions are withdrawn from column 3 through lines 4, 5 and 6, respectively, and are condensed and/or cooled in cooling coils 7, 8 and 9, respectively.

10 is an extraction column which receives the extracting solution near its top through line 11. Into the bottom of extractor 10 is introduced the cooled heaviest distillate fraction from cooler 9 through line 12.

The temperature at the bottom of this extraction column is controlled by cooling coil 29. At a point intermediate between the points of entrance of the treating solution and the heaviest fractions are introduced through lines 13 and 14 the condensed and cooled light and middle fractions from condensers 7 and 8, respectively, the light fraction being admitted at a point above that of entrance of the middle fraction.

As the three fractions flow upward through column 10 they are united, and the resulting mixture of treated distillate emerges at the top through line 15. If desired one or several of the fractions in column 10 may be withdrawn individually or in combination with one or more of the remaining fractions through lines 26 or 27 as the case may be.

The treating solution flows downward through column 10, and as it meets a diminishing stream of organic liquid, the ratio of aqueous solution to organic liquid is increased in the direction of the flow of the extracting solution. The spent aqueous solution, laden with mercaptides, leaves col-

umn 10 through line 16 and is heated in heater 17 to be steam stripped in stripping column 18, preferably in the manner described in the Yabroff-White Patent No. 2,152,724. Steam for stripping may be introduced through line 19, and mercaptans together with spent stripping steam emerge through line 20. Regenerated treating solution returns to the top of column 10 through line 11.

In a further modification of the above sweetening process applicable to sour gasoline distillates free from H_2S which contain organic acids much stronger than mercaptans such as naphthenic acids, thiophenols, alkyl phenols, etc., the distillate may be fractionated to produce one or several heavy fractions containing substantially all of these strong acids, and lighter fractions for example having end boiling points below 175° C. and preferably below 150° C. substantially free of them. The heavy fractions may be pretreated with an alkaline solution under conditions to pre-remove at least those acids which are too strong to be expelled from the caustic alkali solution by steam stripping, thus preventing regeneration of the solution. This pretreatment is so conducted that few mercaptans are removed. Under such conditions, a minimum amount of non-regenerative caustic alkali is consumed.

Thus a heavy fraction may proceed from cooler 9 through line 21 and be treated with aqueous caustic alkali solution, preferably free from solutizer, from line 22. Distillate and aqueous solutions proceed to settling tank 23. Spent caustic alkali is withdrawn through line 24 while pretreated distillate freed from the strong acids but still containing a large portion of mercaptans passes through lines 25 and 12 to extraction tower 10.

The heavy fraction may be further fractionated in a manner not shown into two or more cuts before or after the alkali pretreatment and the fractions so produced may then be introduced into extraction column 10 in the order of the ease of transference of the mercaptans contained in them.

Acids, which would neutralize the extracting solution and render it non-regenerative by steam stripping if allowed to enter the regenerative cycle are those having dissociation constants greater than about 10^{-9} . Even acids having dissociation constants of about 10^{-10} such as many of the alkyl phenols, may only incompletely be removable by steam stripping from their alkali metal salts in strongly alkaline solutions.

Some cracked gasolines contain acetic acid which boils at 118° C. In the treatment of such gasolines, the fraction containing the acetic acid should also be given the caustic pretreatment, as described.

The pre-removal of relatively strong acids from fractions containing them is particularly important in the case of sweetening cracked sour gasolines by extraction of the mercaptans in steam-regenerative systems as the one described above. Cracked gasolines usually contain considerable amounts of alkyl phenols, which tend to build up in the circulating caustic alkali solution to a certain equilibrium concentration, which then remains more or less constant. This equilibrium concentration depends primarily on the concentration of the alkyl phenols in the ingoing hydrocarbon distillate to be treated, the ratio of feed to treating solution, the nature and concentration of the caustic alkali in the aqueous solution and the amount of steam used in the stripping. As-

suming extracting and regenerating conditions to be constant, then with a given extracting solution, the only remaining variable is the concentration of the alkyl phenols in the feed.

Now, alkyl phenolates are good solutizers for mercaptans, and from this point of view, their presence in the extracting solution is quite desirable. However, if alkyl phenolates are allowed to accumulate above a certain concentration, the viscosity of the aqueous solution is raised to an extent so as to cause severe emulsion and carry-over difficulties in the extraction operation. It has been found that for general usefulness, the viscosity of the extracting solution should not be greater than about 37-38 centistokes at the temperature of the extraction.

In order to prevent accumulation of alkyl phenolates in the extracting solution in quantities which cause the viscosity of this solution to exceed the danger limit, it is often necessary materially to reduce the alkyl phenol content of the distillate feed. The maximum permissible amount of alkyl phenols in the feed depends on the variables enumerated above, and can be determined experimentally for any given set of treating conditions. No definite figure for this amount can be given, since obviously it may vary between wide limits with changes in the various factors.

The temperature of extraction in column 10 is preferably maintained between about 0-60° C. At lower temperatures, difficulties may arise due to excessive viscosity, or precipitation of some of the components of the extracting solution, and at higher temperatures the efficiency of mercaptan extraction is greatly diminished.

A further possible modification of the above-described system is to employ refrigeration in that portion of the extraction system in which the heavy gasoline fraction is being separately treated. This can be done by refrigerating the heavy gasoline fraction prior to its entry into the extraction system, or coolers could be incorporated into the particular part of the extraction system itself.

It is understood that use of pumps, heaters, heat exchangers, coolers, condensers wherever necessary is within the skill of the designer for such equipment.

Suitable amounts of extracting solution are normally about 5 to 100 volume percent of the organic liquid feed, although amounts outside of these limits may be employed, if desired.

While the foregoing process has been described as applying particularly to the removal of weak organic acids having dissociation constants below 10^{-5} such as mercaptans, alkyl phenols etc., from hydrocarbon oils, it shall be understood that its usefulness is not limited thereto. For example, it may be applicable to the extraction of lubricating oil.

For example, for the solvent extraction of California lubricating oil with furfural in a twelve stage countercurrent extraction system, three distillate cuts were produced having viscosity indexes of -58, -45 and -38 respectively. The degree of extraction required for each cut to reach the required viscosity index decreases in the order of increasing algebraic viscosity indexes. The fractions so separated are then extracted in accordance with our invention, the fraction of viscosity index -58 being introduced into stage 1 of the countercurrent extractor and flowing through all the stages of the countercurrent extractor. The optimum point of en-

trance can be determined experimentally for each of the remaining fractions. Thus the fractions of viscosity index of -45 and -38 may advantageously be introduced between stages 4 and 5, and 7 and 8 respectively and flow through the remaining stages in combination with the other fractions in countercurrent to the furfural.

Further our process may also be used in processes such as the separation of thiophenols from alkyl phenol mixtures where extraction is accomplished with weak inorganic bases; or in the separation of nitrogen bases from petroleum oils by extraction with aqueous solutions of relatively strong substantially oil insoluble acids such as sulfuric, hydrochloric, formic, acetic, etc.

The material to be extracted may be contained in any liquid which is substantially stable under conditions and for the duration of the treatment and substantially insoluble in and chemically inert to the extracting solvent. When extracting weak organic acids with caustic alkali such organic liquids are, for example, (aside from hydrocarbon oils already mentioned, such as petroleum distillates, coal tar distillates, hydrogenated aromatic hydrocarbons, butanes, pentanes, hexanes, benzene, toluenes, xylenes, etc.) chlorinated hydrocarbons as carbon tetrachloride, ethylene dichloride, chloropropane, etc.; basic organic liquids as quinolines, alkylated pyridines, water insoluble amines, etc.

The preferred method for producing several fractions containing extractable material of different ease of transference is distillation. However, other methods may be applicable, such as fractional precipitation, fractional solvent extraction or any process, physical or chemical which permits segregation of different fractions containing transferable material of different ease of transference.

As previously mentioned, our method is particularly useful in connection with the extraction of extremely weak organic acids, such as mercaptans, with the aid of aqueous caustic alkali solutions containing solutizers for the weak acids. Solutizers have been defined as organic substances which are readily soluble in the aqueous solution of caustic alkali, are good solvents for the weak organic acids, are substantially insoluble in the organic water-insoluble liquid, are inert to the action of strong caustic alkali even at the elevated temperatures of steam stripping, and have boiling temperatures substantially above that of water. Among the most useful solutizers for weak organic acids, the following may be listed: primary, secondary and tertiary amino or hydroxy alkylamines in which the alkyl radicals have 2 to 3 carbon atoms; glycols, amino glycols and diamino, dihydroxy

or amino hydroxy dialkyl ethers or thioethers in which the alkyl groups have 2 to 3 carbon atoms; alkali metal, and preferably potassium salts of fatty acids having preferably from 3 to 5 carbon atoms, or of amino or hydroxy fatty acids having from 4 to 6 carbon atoms, or of phenyl acetic or hydroxy or amino phenyl acetic acids, or of alkyl phenols; or mixtures of the above. Particularly useful are potassium isobutyrate or mixtures of potassium isobutyrate and alkyl phenolates.

Our invention is further illustrated by the examples below:

Example I

A polymer naphtha, specific gravity .6962, having a mercaptan sulfur content of .0700% by weight, was treated as follows:

A portion of the polymer naphtha was fractionally distilled in a ten plate distillation column to yield two fractions: a low boiling fraction having an end boiling point of 120° C. comprising 80% by volume of the total naphtha and a higher boiling fraction of about 20% by volume. The low boiling fraction contained 95.4% of the total mercaptan sulfur originally contained in the polymer naphtha and the remaining 4.6% of the mercaptans comprising the most difficultly extractable mercaptans were concentrated in the higher boiling fraction.

The polymer naphtha was extracted with an aqueous solutizer solution having the following composition: 6N potassium hydroxide, 1.55N potassium isobutyrate and 0.98N potassium alkyl phenolate. The extraction was carried out in a six stage countercurrent treater at 70° F.

Four extractions were performed. In two of these, extractions A and B, the unfractionated portion of the polymer naphtha was treated in the conventional countercurrent way. The volume ratios of the solutizer solution to polymer naphtha were 0.2 and 0.4 respectively. In the other two extractions, C and D, the fractions obtained in the above fractional distillation were treated in accordance with this invention. The ratio of solutizer solution to total naphtha was 0.2. The higher boiling fraction was admitted to the first extraction stage and the low boiling fraction was introduced between the third and fourth stages in run C and the second and third stages in run D. Thus the higher boiling naphtha was treated separately in the first few stages, and the combined fractions were treated together in the remaining stages. Solutizer solution was passed through stages 6 to 1 in countercurrent to the fractions and spent solution was withdrawn from stage 1. The treated naphtha was withdrawn from the sixth stage.

Results were as follows:

Countercurrent extraction of the two fractions of polymer naphtha

Run	Type of extraction	Number of stages for separate extraction of heavy fraction	Total number of stages	Volume ratio of solutizer solution to naphtha		Mercaptan sulphur, percent weight in final treated gasoline blend $\times 10^{-4}$
				For separate extraction of heavy fraction	Overall	
A.....	Conventional.....	None.....	6	0.2	0.2	6. (0)
B.....	Conventional.....	do.....	6	0.4	0.4	3. (2)
C.....	Modified.....	3.....	6	1.0	0.2	2. (2)
D.....	Modified.....	2.....	6	1.0	0.2	2. (3)

It will be noted, particularly when comparing runs B, C and D, that better results may be obtained by the method of this invention with only half of that volume ratio of extracting solvent to solution which is required in regular countercurrent extraction. This results in a decrease of about 50% in the amount of steam required for regeneration of the spent solutizer solution.

Example II

A West Texas straight run gasoline, specific gravity .7369, having a mercaptan sulfur content of 0.0388% by weight, was treated with the aqueous solutizer solution and in the countercurrent extractor of Example I.

The extraction was carried out at 85° F. using a solutizer solution to total gasoline ratio of 0.75.

A portion of the gasoline was fractionally distilled to produce two fractions: a low boiling fraction having an end boiling point of 152° C. being about 70% by volume of the total gasoline and a higher boiling fraction of about 30% by volume. The low boiling fraction contained 56% of the total mercaptan sulfur and the higher boiling fraction contained 44% of the mercaptan sulfur.

Two extractions E and F were performed. In run E the unfractionated portion was extracted in the conventional countercurrent way. In run F the fractionated portion was treated according to the split extraction method of this invention. In the last run, the higher boiling fraction was separately extracted in stages 1 to 3. The low boiling fraction was introduced between stages 3 and 4, and the combined fractions were extracted together in the remaining stages. The solutizer solution was passed through stages 6 to 1 in countercurrent to the fractions and spent solution was withdrawn from stage 1. The treated gasoline was withdrawn from the sixth stage.

Results were as follows:

Countercurrent extraction of the two fractions of West Texas straight run gasoline

Run	Type of extraction	Number of stages for separate extraction of heavy fraction	Total number of stages	Volume ratio of solutizer solution to gasoline		Mercaptan sulphur, percent weight in final treated gasoline blend $\times 10^{-4}$
				For separate extraction of heavy fraction	Overall	
E	Conventional	None	6		0.75	9. (3)
F	Modified	3	6	2.7	0.75	3. (1)

In this case, an overall solutizer solution-gasoline volume ratio in excess of 1.5 is required in conventional countercurrent extraction to obtain the same result as was secured by split extraction with a ratio of 0.75. The steam required for regeneration is reduced in about the same proportion.

We claim as our invention:

1. In the process of separating weak organic acids contained in a water-insoluble organic liquid which is substantially inert toward alkali metal hydroxide, by extracting with an aqueous solution of alkali metal hydroxide, the improvement comprising fractionating said solution to produce at least two fractions containing portions of said acids, which portions have different degrees of ease of transference toward said aqueous solution of alkali metal hydroxide, flowing said solvent through an extraction zone and

5 withdrawing it therefrom, introducing into said zone at different points in the direction of flow of said aqueous solution said fractions in the order of their decreasing ease of transference, flowing said fractions through at least part of said zone in countercurrent to said aqueous solution combining at least some of said fractions within said zone, and withdrawing them.

2. In the process of separating mercaptans and 10 relatively strong organic acids having dissociation constants greater than 10^{-9} from a hydrocarbon distillate containing same by extraction with an aqueous solution of alkali metal hydroxide in a regenerative system which comprises extracting 15 in an extraction system said distillate with said aqueous solution to produce a spent solution containing mercaptides, regenerating said spent solution by steam stripping and recirculating the regenerated solution for further extractions, the improvement comprising fractionating said hydrocarbon distillate to produce at least two fractions containing mercaptans of different ease of transference, at least one fraction being substantially free of and the remaining fractions having accumulated in them said strong organic acids having dissociation constants greater than 10^{-9} , pretreating only the latter fractions to remove strong acids and to produce pretreated fractions having retained a substantial portion of the mercaptans, flowing said aqueous solution through an extraction zone, introducing into said zone at different points in the direction of flow of said aqueous solution said pretreated fractions and the fraction originally free from said strong acids 20 in the order of the decreasing ease of transference of the mercaptans which they contain, flowing said fractions through said zone in countercurrent to the flow of said solvent, combining said fractions within said zone, and separately withdrawing the resulting solvent and combined fractions.

3. In the process of separating mercaptans and relatively strong organic acids having dissociation constants greater than 10^{-9} from a gasoline distillate containing same by extraction with an aqueous solution of alkali metal hydroxide in a regenerative system which comprises extracting in an extraction system said distillate with said aqueous solution to produce a spent solution containing mercaptides, regenerating said spent solution by steam stripping and recirculating the regenerated solution for further extractions, the improvement comprising fractionally distilling said hydrocarbon distillate to produce two fractions, a low boiling fraction having an end boiling point below 175° C. being substantially free of said strong organic acids, and a smaller high boiling fraction boiling above about 175° C. containing substantially all said strong organic acids having dissociation constants greater than 10^{-9} ,

pretreating the higher boiling fraction with aqueous caustic alkali to remove strong acids and to produce a pretreated fraction having retained a substantial portion of the mercaptans, flowing said aqueous solution through an extraction zone, and withdrawing it therefrom, introducing the smaller high boiling fraction into one end of said extraction zone near the point of withdrawal of the aqueous solution, introducing the low boiling fraction at a point intermediate between the entrance of the aqueous solution and the higher boiling fraction, flowing both fractions in countercurrent to the flow of said aqueous solution, combining said fractions within said zone, and withdrawing the resulting combined fractions.

4. The process of claim 1 in which the organic acids have dissociation constants of less than 10^{-5} .

5. In the process of separating mercaptans contained in a hydrocarbon distillate by extracting with an aqueous solution of an alkali metal hydroxide, the improvement comprising fractionally distilling said hydrocarbon distillate to produce at least two fractions containing portions of said mercaptans, said portions having different degrees of ease of transference toward said aqueous solution, flowing said aqueous solution through an extraction zone, introducing into said zone at different points in the direction of flow of

said aqueous solution said fractions in the order of their decreasing ease of transference of the mercaptans which they contain, flowing said fractions through said zone countercurrent to the flow of said solvent, combining said fractions within said zone, and separately withdrawing the resulting solvent and combined fractions.

6. In the process of separating mercaptans contained in a hydrocarbon distillate by extracting with an aqueous solution of an alkali metal hydroxide, the improvement comprising fractionally distilling said hydrocarbon distillate to produce two fractions of different volumes, a large low boiling and a smaller higher boiling fraction, flowing said aqueous solution through an extraction zone, and withdrawing it therefrom, introducing the smaller fraction into one end of said extraction zone near the point of withdrawal of the aqueous solution, introducing the low boiling fraction at a point intermediate between the entrance of the aqueous solution and the higher boiling fraction, flowing both fractions in countercurrent to the flow of said aqueous solution, combining said fractions within said zone and withdrawing the resulting combined fractions.
